UNITED STATES PATENT OFFICE

WALTER LOUIS KRAHL, OF MONTCLAIR, NEW JERSEY, ASSIGNOR, BY MESNE ASSIGNMENTS, TO ARCTURUS RADIO TUBE COMPANY, OF NEWARK, NEW JERSEY, A CORPORATION OF DELAWARE

THERMIONIC TUBE CONNECTING MEANS

Application filed December 10, 1927. Serial No. 239,027.

This invention relates to a thermionic alternating current tube and method and means of connecting the same in a circuit originally wired for direct current operation. The invention is particularly adapted for use in connection with a thermionic tube shown in my application, Serial No. 156,946, entitled "Power operated vacuum tube construction and circuit therefor."

10 In changing a direct current radio set over to alternating current operation, by substituting alternating current tubes for the direct current tubes, it is necessary generally, to somewhat alter the circuit wiring of the set, and particularly the leads which are connected to the filaments of the tubes for energizing the same.

One means for making this change is to provide entirely separate leads for the alternating current supply and leaving the direct current leads as they are in the circuit without using the same. If an alternating current tube is used having contacts on the base corresponding to the contacts of a direct current tube, these tube contacts have sometimes been insulated from the corresponding contacts of the socket by providing an adapter which has a base similar to a tube base to fit into the socket and a socket adapted to receive the vacuum tube and is provided with intermediate connections so that any desired change in the connections of the tube terminals may be made by means of terminals mounted on the adapter itself. Such adapters necessarily constitute additional pieces of equipment which increase the cost of changing over a set and have other disadvantages such as raising the tube with respect to the original socket so that a set designed with limited head-room for the tubes will be impossible to change over because the added height of the tube will prevent the insertion of the same.

One of the primary objects of the present invention therefore, is to permit the change of a radio set from direct current to alternating current operation by the substitution of alternating current tubes without the use of adapters; the tubes being designed to fit into standard sockets.

Another object of the invention is to provide a tube having a base which may be readily changed so that auxiliary filament terminals may be directly applied to the tube.

Another object of the invention is to provide a tube with removable terminals on the base thereof which may be quickly and easily replaced with insulating terminals adapted to electrically separate the filament terminals from the corresponding contacts of a socket 60 adapted to receive the tube.

Another object of the invention is to provide a connection harness with means to readily attach the same to the filament terminals on a plurality of tubes and which may be supplied as an auxiliary part of the wiring of a radio set.

Another object of the invention is to provide means to apply an individual potential on the grid of the detector tube of a radio set 70 without otherwise changing the permanent wiring of the set.

Another object of the invention is to provide a means for controlling the volume of the output of the radio set when the original 75 A-battery circuit which is connected to the volume control is no longer used.

Other objects and objects relating to economies of the construction of various parts will appear as the description of the invention 80 proceeds.

One embodiment of the invention has been illustrated in the accompanying drawings, in which

Fig. 1 is a circuit diagram illustrating the 85 application of my invention;

Fig. 2 is a plan view of the harness shown connected to the tubes of a radio set;

Fig. 3 is an elevation of the lower part of an alternating current tube, part of which is 90 shown in section to illustrate the removable terminals;

Fig. 3A is an elevation of one of the conductor terminals;

Fig. 4 is a bottom view of an alternating 95 current tube embodying the invention with the auxiliary terminals attached;

Fig. 5 is an elevation of a grid leak showing the insulating clip attached thereto;

Figs. 6 and 7 are an end view and an eleva- 100

tion, respectively, of a clip for connecting to another type of grid leak;

Fig. 8 is a circuit diagram of a modified form of volume control adapted to be used in connection with my invention; and

Figs. 9 and 10 are an elevation and plan view, respectively, of a means for connecting the volume control shown in Fig. 8.

In carrying out the invention, I provide alternating current tubes with removable contact pins in their bases. This is illustrated in Fig. 3 of the drawings wherein the glass envelope 10 is mounted in the usual moulded base 11 in which the plate and grid contact terminals are set. The connections 12 to the filament, however, are brought down to two thimbles 13 which are moulded in the base 11 in the position ordinarily occupied by the filament terminals and which are drilled and tapped to receive the threaded end 14 of the filament contact terminal 15, Fig. 3A. The connection from the filament to the thimbles is preferably made by providing a hole 16 in the bottom of the base adjacent each thimble and placing one end of a thin flat conductor or bus-bar 17 adjacent the edge of the hole, the other end of which conductor is provided with an opening 18 large enough to receive easily the threaded end 14 of the conducting pin 15, but not as large as the diameter of the pin itself, so that when the pin is screwed in place, it will hold the conductor firmly against the thimble 13. The wire 12 from the filament of the tube preferably passes through the hole 19 and is soldered to the conductor or bus-bar 17 so that the latter is held in place solely by the conducting pin and the soldered connection.

I have provided also insulating pins which may be attached to the base of the tube as indicated in Fig. 3 in place of the conductor pins. These pins 20 have a threaded end 21 similarly to the conductor pins 14, but the outer end 22 is smaller in diameter, and preferably provided with knurled ridges 23 or otherwise formed irregular on the surface thereof and surrounded by insulating material 24 which may be moulded thereon and which has a diameter substantially the same as the diameter of the conducting pin 15.

The insulating pin 20 when the tube is placed in a standard flat socket, insulates the filament terminals of the tube from the corresponding contact terminals of the socket and in order to make the proper connections to the filament terminals of the tube, I have provided auxiliary filament terminals 25 which are preferably formed of thin sheet metal such as copper or brass, and constitute a strip 25 having a hole 27 in one end substantially the same size as the hole 18 in the connector or bus-bar 17 by which the strip may be rigidly secured against the thimble and electrically connected thereto by the insulating pin. The auxiliary terminal is pro-

vided at its outer end with a bent or curved up end to form a socket 28 to receive a conducting wire to which it may be soldered.

It will be seen from the above, that when the filament pins on the tube have been replaced by insulating pins and the auxiliary terminals provided, and the tube is placed in a standard socket, the filament terminals of the tube will be insulated from the socket, but filament current may be supplied by means of the auxiliary filament terminals.

Where a plurality of tubes are used in a set, I have found it convenient to connect the two filament terminals 29 and 30 (Fig. 2) of each tube to two wires 31 and 32 respectively, which may have the auxiliary terminals 25 soldered to them at certain properly spaced intervals. These two wires 31 and 32 should preferably be twisted together and may be included with two other wires 33 and 34, the purpose of which will be explained hereafter, in a cable 35, which may be led outside the casting for the circuit in order to make the connections to the alternating current source and batteries.

The wire 33 in this cable has one end connected to the wire 32 adjacent the auxiliary terminal 25 which is intended for connection to the filament terminal of the detector tube having substantially cathode potential. The other end of the wire extends out of the opposite end of the cable and forms the connection from the set to the negative terminal of the B-battery.

It has been found preferable in the operation of the alternating current tube above referred to, to provide the grid of the detector tube with a positive D bias, while the grid of the amplifier tubes may be charged negatively. If all of the grid returns are connected together, and given a negative potential, it is necessary in some way, to break the grid circuit of the detector tube in order to provide this grid with a positive potential. In order to accomplish this result, I have provided an insulating connector 36 which is preferably formed of a thin flat metal plate 37 having an opening 38 therein and provided at one side with insulating material 39. The insulating material 39 may conveniently be formed of a short piece of rubber tube, while a flange 40 around the edge of the opening 38 in the plate forms a convenient means of attaching the rubber insulator.

This plate may be placed between the end of the grid leak 41 furthest from the detector tube and the support 42 therefor so that the metal plate 37 comes in contact with the grid leak 41, while the rubber tube 39 contacts with the support 42. The other end of the plate 37 is provided with a bent or rolled portion 43 to receive the wire 34 for connecting in the circuit, which wire may be soldered to the plate. When this connector 36 is in place, between the end of the grid leak 41 and the

support 42, the original permanent connection of the set from the grid leak support is broken, and if therefore, a positive D potential is placed, on the wire 34 leading to the 5 connector, the grid of the detector tube will be positively charged.

This wire 34, therefore, is contained in the cable 35, above mentioned, which forms a convenient harness for quickly changing a set 10 wired for direct current over to alternating current operation.

Where the grid leak is of the fuse type, having cylindrical metallic ends 44, which are sprung into U-shaped clips, the insulating 15 connector for the grid leak may be formed, as in Fig. 6, of a flat strip 45 of metal riveted or otherwise attached to a somewhat wider flat strip 46 of insulating material such as fibre, both of which may be bent around the 20 cylindrical end of the grid leak before it is sprung into the U-shaped clip, the insulating material coming between the clip and the metallic plate of the connector.

The invention is diagrammatically shown 25 adapted to the circuit of a well-known direct current receiving set in which the light full lines represent the permanent wiring of the set, while the heavy lines indicate the additional wiring necessary for the use of alternating current tubes. The auxiliary grid connector 36 is shown connected through the cable 35 to 4½ volts positive on the D-battery, while the negative potential is placed on the 30 radio frequency tubes by simple connecting 35 the A-battery terminals of the set together, and to a C-battery of -1½ volts. The negative bias on the two audio tubes may be made somewhat larger, if desired, by the addition 40 of more C-battery voltage and I have found in this instance, that about 27 volts on the last audio stage will give satisfactory results.

It will be noted from an inspection of Fig. 1 that inasmuch as the permanently wired filament connections 47 and 48 are not used 45 with the present invention, the volume control which comprises a rheostat 49 is also thrown out of service. I have, therefore, found it necessary to provide an auxiliary volume control and such a control comprises 50 a potentiometer 50 connected between the antenna and the ground, while the variable arm 51 of the potentiometer is connected to the antenna terminal on the set. In connecting this volume control into the circuit, therefore, it is necessary only to disconnect 55 the antenna from the set, connecting the arm of the potentiometer in its place, and then to connect the antenna to one end of the potentiometer coil and the ground to the other 60 end. While such a volume control gives excellent results, any other preferred type may be used, such as a variable resistor 52 of from 0 to 200,000 ohms connected across the secondary 53 of the radio frequency transformer 54 (see Fig. 8) which is connected to

the grid of the tube immediately preceding the detector tube. A convenient way to connect the resistor 52 is to connect one end directly to the grid terminal of the tube immediately preceding the detector tube. This 50 may be accomplished by means of a connector clip 55 shown in Figs. 9 and 10 which may be provided with an opening 56 to fit over the grid terminal 57 of the tube. A plurality of lugs 58 may be left uncut from the 55 opening 56 so that the lugs will be bent downwardly when the clip 55 is forced over the end of the terminal 57, thus insuring a tight connection. The end of the clip 55 may be rolled similarly to the terminal 25 to form a 60 socket 59 to receive the end of the wire attached to the resistor. The other terminal of the variable resistor may be connected to the ground terminal of the set.

It is evident from the above description 65 that the invention provides a very convenient and efficient method of changing a standard direct current radio set over to alternating current operation in a minimum of time. The steps necessary to make such change 70 being as follows:

First, the direct current tubes are removed 75 from the set; second, the filament terminals on the alternating current tubes are replaced by the insulating terminals at the same time 80 securing the auxiliary terminals with the harness attached in place at the base of the tubes. The tubes are then inserted in the 85 sockets, the harness cable being led out through any convenient wire opening at the 90 back of the set for connection to the transformer 60, the primary of which is connected to the alternating current source. The 95 grid leak connector is then slipped between the outer end of the grid leak and the support 100 therefor and the volume control is connected between the antenna and the set as already described. When the A-battery terminals of the set are connected together, and to a negative terminal of a C-battery, as indicated in Fig. 1, and the other end of the 105 grid leak connector to a positive D terminal of the B-battery, the set is ready for operation.

The A plus lead of a receiver may be used 110 in place of the extra lead in the cable for the connection to the positive D potential in radio sets wherein this A plus lead is connected to the detector grid return and to no other points in the circuit except the plus filament 115 terminals of the tube sockets. In this case 120 a three wire cable would be used.

While I have shown and described the invention in connection with a specific type 125 of alternating current tubes, and a particular structure for direct current operation, it is evident that the invention may be applicable to any number of different direct current circuits, or other types of alternating current tubes, or it may be applicable in 130

changing one type of direct current circuit to another type of direct current circuit, and I do not desire to limit myself, therefore, to the specific construction shown and described, but to interpret the invention broadly, within the scope of the appended claims.

Having thus described my invention, what I claim as new and desire to secure by Letters Patent is:

10. 1. In a connection harness for use in adapting a direct current radio circuit for alternating current operation, a four wire cable, taps on two of said wires adapted to be connected to the filament terminals of the tubes, an insulating clip on the end of a third wire adapted to electrically contact with one end of a grid leak and insulate said grid leak from its normal support at that end, and having the fourth wire connected to one of the first two wires at a point adjacent the tap for connection to the filament of the detector tube.
15. 2. In a connection harness, for use in adapting a direct current radio circuit for alternating current operation; a cable, two wires in said cable having taps at spaced intervals thereon adapted to be connected to the filament terminals of said tubes, a third wire in said cable, an insulating clip at the end of said wire adapted to fit between one end of a grid leak and the support therefor and to insulate that end from said support, a fourth wire in said cable connected to one of said first two wires.
20. 3. In a connection harness for use in adapting a direct current radio circuit for alternating current operation, a cable containing a plurality of wires, taps on two of said wires adapted to be connected to the filament terminals of the tubes, and another of said wires connected to one of said first two wires at a point adjacent the tap for connection to the filament of the detector tube.
25. 4. In a harness for use in connecting a direct current radio circuit for alternating current operation, a four wire cable, taps on two of said wires, means to directly connect said taps to the filament terminals of alternating current vacuum tubes, means on said terminals to insulate said terminals from the contacts of the socket when the tube is inserted therein, and an insulating clip on the end of a third wire adapted to electrically contact with one end of a grid leak and insulate said grid leak from its normal support at that end, the fourth wire being connected to one of the first two wires at a point adjacent the tap for connecting the filament of the detector tube.
30. 60. In testimony whereof, I affix my signature.
WALTER LOUIS KRAHL.
